205,109

COMBINED STOCK AND TILLER FRAME FOR YACHTS

David Nisbet Binks, 7 Athelney Ave., Brighton,
South Australia, Australia

Filed Sept. 22, 1965, Ser. No. 87,113

Term of patent 14 years

(Cl. D71—1)

The figure shown is a perspective view of a combined stock and tiller frame for yachts.

I claim:

The ornamental design for a combined stock and tiller frame for yachts, as shown.

References Cited by the Examiner

UNITED STATES PATENTS

D. 142,174 8/1945 Pearce ----- D35—2
D. 203,601 2/1966 Otteman ----- D33—8

10,085	10/1853	Griffith -----	172—776
419,946	1/1890	Hendricks -----	172—776
2,367,186	1/1945	Colica -----	114—62
2,861,533	11/1958	Thomas -----	114—62
3,057,316	10/1962	Hansen -----	114—39
3,191,569	6/1965	Coombe -----	114—39
3,234,669	2/1966	Kachnik et al.

WALLACE R. BURKE, Primary Examiner.
BERNARD ANSHER, Assistant Examiner.